UNITED STATES PATENT OFFICE.

ANDREAS BOTHE, OF ORELAND, PENNSYLVANIA, ASSIGNOR TO KLEEN PRODUCTS COMPANY, INC., OF NORTH WALES, PENNSYLVANIA, A CORPORATION OF DELAWARE.

DESIGN FOR A SPOON OR SIMILAR ARTICLE.

Application filed July 27, 1921. Serial No. 488,020. Term of patent 14 years.

To all whom it may concern:

Be it known that I, ANDREAS BOTHE, a citizen of the United States, residing at Oreland, in the county of Montgomery and State of Pennsylvania, have invented a new, original, and ornamental Design for Spoons or Similar Articles, of which the following is a specification, reference being had to the accompanying drawing, forming part hereof.

Figure 1 is a perspective view of the back

of a spoon or similar article, and Fig. 2 is a similar view of the front of a spoon or similar article, and Figs. 3 and 4 are transverse sectional views taken on the lines 3-3 and 4-4 respectively and drawn to an enlarged scale, showing my new design.

I claim:

An ornamental design for a spoon or similar article, as shown.

ANDREAS BOTHE.
